UNITED STATES PATENT OFFICE.

TERRENCE REYNOLDS, OF ATALLA, ALABAMA.

DUMPING-CAR.

SPECIFICATION forming part of Letters Patent No. 299,263, dated May 27, 1884.

Application filed November 9, 1883. (No model.)

To all whom it may concern:

Be it known that I, TERRENCE REYNOLDS, of Atalla, in the county of Etowah and State of Alabama, have invented certain new and 5 useful Improvements in Dumping-Cars, of which the following is a full, clear, and exact description.

Reference is to be had to the accompanying drawings, forming part of this specification, in 10 which similar letters of reference indicate corresponding parts in all the figures.

Figure 1 is a side elevation, partly in section, of a car to which my improvement has been applied. Fig. 2 is a front elevation of the same. 15 Fig. 3 is a plan view of a part of the same. Fig. 4 is a sectional side elevation of the same, taken through the line $x-x$, Fig. 2, and shown as tilted.

The object of this invention is to facilitate 20 the unloading of cars in mines and other places where the loads are to be dumped.

The invention consists in the construction, arrangement, and combination of parts, all as hereinafter described and claimed.

25 A represents the tilting platform, which is journaled at points a little in front of its center to a stationary frame, B.

C is the stationary platform, from which the car passes to the tilting platform A, and which 30 is provided with rails D. The rails E of the tilting platform A are in line with the rails D when the said tilting platform is in a horizontal position. The forward ends of the rails E are curved upward, as shown in Fig. 1, to receive 35 the wheels F of the car G and prevent the said car from moving any farther forward.

To the stationary frame B is attached a cross-bar, H, in such a position as to receive the forward end of the platform A when the said 40 platform is tilted and limit the downward movement of the said end. The body of the car G is strengthened by iron straps I, which cross the bottom and extend up the sides of the said body.

45 To the central and forward straps I, a little above the central line of the car-body, are attached iron straps J, the ends of which project beyond the forward ends of the sides of the car-body, and are bent inward at right angles, 50 enough space being left between the said inwardly-projecting ends and the ends of the

sides of the car-body to receive the projecting ends of an iron bar, K, attached to the forward end-board, L, the straps J and bar K thus forming a fastening to secure the said end- 55 board in place.

To the outside and at the upper end of the end-board L is secured the iron plate M, the ends of which project beyond the side edges of the end-board L, and are bent rearward at 60 right angles to form the arms b b, enough space being left between the edges of the end-board and the said rearwardly-projecting arms to receive the forward ends of the side-boards a a of the car-body, as shown in Fig. 3. 65

Passing through the arms b b, and reaching from arm to arm, is the rod N, which serves to hold the arms b b from spreading, and the upper edges of the side-boards a a of the car-body are notched, as shown at c c, to receive 70 the rod N when the end-board L is in place, so that the said rod serves also to retain the end-board at its upper edge without other fastenings.

The fastening-plate K being narrow and the 75 notches c shallow, and these being the only fastenings for holding the end-board L in place on the car-body, it will be seen that a very slight upward movement of the end-board L will release it from the car-body, so that it can be 80 taken out in any place in a gangway, when it can be raised the width of the plate K and notches c, which is of great advantage where the end-board has to be taken out by hand, as in case the car should get off from the track, and also where 85 the lifter O, for automatically lifting and replacing the end-board L, is used in dumping.

The lifter O is a U-shaped frame, of iron or wood, hinged to the forward end of the frame B. It is provided in the center with the point 90 P, and is attached by the rod R and eye-plate d to the tilting platform A, so that when the platform A is in horizontal position the lifter O will be held in inclined position, as shown in Fig. 1, bringing the point P in line with the 95 opening Q, made in the end-board L, so that as the car G is pushed upon platform A, and a little before it reaches the tilting position, the point P will enter the opening Q, thus connecting the end-board L and lifter O 100 together. On approaching the tilting-point of platform A and in tilting, the car G will force

the lifter O forward to a vertical position, causing point P to move in an upward arc of a circle, causing it to automatically lift the end-board L out of the car-body and suspend it above 5 the descending end of the car, as shown in Fig. 4, where it will be held until the platform A and car G are brought again to horizontal position and the car started off from the platform, which movement of the car and platform 10 will draw the lifter O to its normal inclined position and cause it to automatically lower and replace the end-board L on the car-body. The lifter O is stopped at the proper angle in its backward movement by the stop-pins e e, 15 fitted in it above the platform B, which pins are adapted to come upon the upper edge of said platform, as shown in Fig. 1. The slight movement of the end-board L necessary to lock it with and unlock it from the straps J and notches 20 c obviates all danger of the end-board binding in the car-body, and thus makes the automatic lifting and replacing of the end-board in dumping very reliable and practical. Besides, by the means described for holding the 25 end-board, the open end of the car is left entirely free of all obstruction likely to retard or break the coal or other material in dumping.

Having thus described my invention, what I

claim as new, and desire to secure by Letters 30 Patent, is—

1. The end-board L, having central plate, K, projecting past the edges of the board, and provided near its upper end with arms b and rod N, in combination with the car-body G, 35 notched, as at c, and provided with the holding-plates J, substantially as and for the purposes described.

2. The car-body G, provided with the bent straps J, in combination with the end-board 40 L, provided with the plate K, substantially as and for the purposes set forth.

3. The lifter O, pivoted to the frame B, and provided with the point P, and attached to tilting platform A by rod R, substantially as and 45 for the purposes set forth.

4. The lifter O, attached to tilting platform A, and provided with point P, in combination with the end-board L, provided with opening Q, substantially as and for the purposes set 50 forth.

5. The lifter O, pivoted to frame B, and provided with stop-pin e, to limit its angle of inclination, substantially as described.

TERRENCE REYNOLDS.
